BUILDING BLOCK

Erle T. Putnam, Detroit, Mich., assignor to
Libbey-Owens-Ford Glass Company, Toledo,
Ohio, a corporation of Ohio

Original application May 25, 1940, Serial No.
337,276. Divided and this application Sep-
tember 4, 1941, Serial No. 409,544

4 Claims. (Cl. 72—35)

The present invention relates to an improved type of building unit adapted for use in the construction of interior and exterior walls.

This application is a division of my copending application Serial No. 337,276, filed May 25, 1940, entitled "Building blocks."

The building unit herein provided comprises a composite block including a body portion formed from a cementitious material, such as concrete, Haydite, or the like, and an ornamental facing therefor. The ornamental facing is preferably secured to the body portion by an interposed layer of adhesive material, such as an asphaltic mastic cement, and also by mechanical fastening means in the form of metal holders engaging both the ornamental facing and the body portion. In constructing a wall with building blocks of this invention, the blocks are adapted to be laid up in courses in substantially the same manner as cut stone, granite, or terra-cotta, being preferably anchored to a rear or foundation wall.

Generally, it is the aim of the invention to provide a composite building block of the above character embodying novel features of construction and arrangement which will not only greatly enhance the ornamental appearance of the block but which will also improve its structural characteristics.

Another object of the invention is the provision of a building block of the above character having an ornamental facing including one or more sheets or plates of opaque structural glass of the same or different colors and with which may be associated metal moldings or facing strips which not only give to the block a more attractive, finished appearance but also adapt it to varied uses.

Another object of the invention is the provision of a building block of the above character including an ornamental facing composed of two or more sheets or plates of opaque structural glass arranged in spaced edge to edge relation and held in proper position with respect to one another by metal molding strips having cushioned engagement with the edges of the glass sheets or plates to prevent marring or injury thereto as well as permitting relative expansion and contraction thereof.

Another object of the invention is the provision of a building block of the above character adapted for use as a corner block and embodying ornamental facings disposed at an angle to one another and having associated therewith in a novel manner a metal corner molding of improved construction.

A further object of the invention is the pro-

vision of a building block of the above character having associated therewith a metal coping member of improved construction and to which a suitable flashing material may be readily and securely attached.

A still further object of the invention is the provision of a building block of the above character to which a metal sash or store front construction may be readily and conveniently secured without placing any load or strain upon the ornamental facing.

Other objects and advantages of the invention will become more apparent during the course of the following description, when taken in connection with the accompanying drawings.

In the drawings, wherein like numerals are employed to designate like parts throughout the same:

Fig. 1 is a perspective view of a building block constructed in accordance with the invention and adapted for use as a corner block;

Fig. 2 is a vertical sectional view through a portion of the block taken substantially on line 2—2 of Fig. 1;

Fig. 3 is a horizontal perspective sectional view taken substantially on line 3—3 of Fig. 1;

Fig. 4 is a front view of a modified type of building block;

Fig. 5 is a vertical sectional view taken substantially on line 5—5 of Fig. 4;

Fig. 6 is a horizontal sectional view showing the provision of a metal molding or spacer strip between two sheets or plates of glass;

Fig. 7 is a sectional view showing a modified type of metal edge holder;

Fig. 8 is a horizontal transverse sectional view of a building block having a metal sash or store front construction associated therewith; and

Fig. 9 is a perspective sectional view of a building block having associated therewith a metal coping member.

Referring now to the drawings and particularly to Figs. 1, 2 and 3, there is illustrated a building block construction adapted for use as a corner block and comprising a body portion 15 preferably formed from a cementitious material, such as concrete, Haydite, or the like. The body portion 15 is shown as being substantially L-shaped having a relatively wide front portion 16 and a relatively narrow end portion 17 disposed at substantially right angles to said front portion. It will of course be appreciated that the body portion 15 need not necessarily be L-shaped and, further, that the end portion 17 thereof can be disposed

at any desired angle relative to the front portion 16.

The front and end portions 16 and 17 of body portion 15 are provided with the ornamental facings 18 and 19 respectively, while arranged at the corner of said front and end portions, between the adjacent ornamental facings 18 and 19, is a metal corner bead or molding 20.

Each ornamental facing 18 and 19 may consist of a single sheet or plate of opaque structural glass or other desired material, but, as here shown, is made up of three spaced sheets or plates of glass 21, 22, and 23 with which are alternately arranged the two metal molding or facing strips 24 and 25. The glass face plates 21, 22, and 23 are preferably secured to the body portion 15 by a relatively thick, substantially uniform layer of adhesive material 26, such as asphaltic mastic cement, which serves not only to bind the glass to the body portion but also permits relative expansion and contraction between the two without danger of the glass sheets or plates becoming broken or accidentally displaced. The layer of mastic 26 also serves to cushion the glass sheets or plates against shock and blows thereby increasing its resistance to breakage.

The metal molding strips 24 and 25 are arranged alternately with the glass sheets or plates and greatly enhance the attractiveness and ornamental appearance of the block. These metal strips may be of rolled, cast or extruded metal and formed of aluminum, bronze, iron, etc. Each metal strip comprises a face piece 27 having the desired cross sectional contour and overlapping the adjacent marginal edge portions of the glass plates; said face piece being provided along its opposite edges with inturned flanges 28 and 29 which engage the front faces of the glass plates. Formed integral with the face piece 27 and extending rearwardly therefrom is a longitudinally extending leg 30 embedded within a mortar insert 31 arranged in a recess 32 in the body portion 16 of the block. Arranged at opposite sides of the anchoring leg 30 are strips of cushioning material 32' which engage the adjacent edges of the glass sheets or plates. Other suitable cushioning means may of course be provided.

The metal corner bead or molding 20 comprises a substantially triangular shaped body member 33 disposed between the adjacent edges of the ornamental facings 18 and 19 which are carried by the front and end portions 16 and 17 respectively of the body portion 15 as best shown in Fig. 3. The outer face of the body member 33 of the corner molding is curved transversely to provide a rounded corner, while extending laterally from the apex of the triangular body member 33 are the wing portions 34 and 35 disposed behind the ornamental facings 18 and 19 respectively and engaging the inner surfaces of the glass facing sheets or plates. The wing portions 34 and 35 are interposed between the ornamental facings and body portion of the block and the front surfaces thereof are disposed at an angle to one another corresponding to the angle at which the ornamental facings are arranged. Formed integral with the wing portions and extending rearwardly therefrom is an anchoring leg 36 which is embedded in the cementitious body portion 15 of the block.

The triangular shaped body member 33 of the corner molding 20 is provided with longitudinally extending lips 37 and 38 which cooperate with the front surfaces of the wing portions 34 and 35 respectively to provide relatively shallow chan-

nels within which are disposed strips 39 and 40 respectively of a suitable cushioning material, such as asphalt impregnated cork, although they may be of rubber, rubber composition, etc. The strips of cushioning material 39 and 40 engage the adjacent edges of the glass sheets or plates 21, 22, and 23 of the ornamental facings 18 and 19. It will be noted that the thickness of the cushioning strips 39 and 40 is such that they project beyond the lips 37 and 38 of the metal molding so that the said lips do not contact the edges of the glass sheets or plates.

Arranged along the top and bottom of each ornamental facing 18 and 19 and also along the outer vertical edge thereof are the metal edge holders 41 for mechanically securing the ornamental facing to the body portion. Each metal edge holder 41 comprises a longitudinally extending channel shaped portion 42 which is received between the ornamental facing and body portion of the block (Fig. 2). The outer wall 43 of the channel portion 42 constitutes a shoulder which abuts the rear surfaces of the glass facing sheets or plates and extending forwardly therefrom and at substantially right angles thereto is a flange 44 disposed opposite the edges of said glass facing sheets or plates and terminating in an inwardly directed lip 45.

The peripheral edges of the glass sheets or plates constituting the ornamental facing are preferably square and engaging said edges are strips 46 of suitable cushioning material which may also consist of asphalt impregnated cork. These cushioning strips serve to protect the edges of the glass and act to prevent chipping or spalling of the glass during the setting of the block in place in a wall. As shown in Fig. 2, the cushioning strips 46 terminate inwardly of the outer surfaces of the glass sheets or plates and also that the shoulders 43, flanges 44, and lips 45 of the metal holders define substantially U-shaped channels in which the cushioning strips are received.

The inner wall 47 of channel portion 42 of each metal edge holder 41 constitutes a shoulder which engages the outer surface of the body portion 15; said shoulder projecting slightly beyond the body portion and extending at substantially right angles with respect thereto is a relatively wide, flat load bearing portion 48 disposed opposite the body portion of the block. Formed integral with and constituting a continuation of the load bearing portion 48 is an inwardly directed flange 49 which is embedded in the body portion 15.

Due to the fact that the load bearing portions 48 of the metal holders 41 project beyond the adjacent edges of the ornamental facing, there will be formed around the edges of the body portion a continuous load bearing ledge 50 which also projects slightly beyond the edges of said facing. Consequently, when the blocks are laid up in courses in a wall, with the load bearing portions 48 of vertically adjacent blocks in engagement with one another, the adjacent ornamental facings will be spaced from each other and in this space is adapted to be inserted a suitable pointing or calking material.

When the blocks are mounted in place in the above manner, the structural load of the wall will be supported entirely by the body portions 15 of the blocks, with none of the load being placed upon the ornamental facings. In other words, the load of one block is transferred directly to the body portion of the next lower block, and each block takes the full strain of the blocks above it.

Instead of the ornamental facings 18 and 19 being formed of alternately arranged glass plates and metal strips, such facings may be made up of strips of glass of different colors as shown in Fig. 4 wherein the glass plates are designated 51, 52, and 53. Such an arrangement may be incorporated in a corner block of the type illustrated in Fig. 1, or in a face block as shown in Fig. 4 wherein metal holders 54, similar to metal holders 41 above described, are arranged around the four edges of the block. The plates of glass 51, 52, and 53 may be spaced from one another by strips of cork or other cushioning material 55 (Fig. 5) covered by pointing or calking material 56.

If desired, instead of using the cushioning strips 55, metal molding or spacer strips may be employed as illustrated in Fig. 6. The metal spacer strip herein shown comprises a substantially rectangular body member 57 from which extend the lateral wing portions 58 and 59 disposed behind the glass face plates 51 and 52 respectively and engaging the rear surfaces thereof. The body member 57 is provided along the outer edge thereof with the relatively narrow lips 60 and 61 which cooperate with the wing portions 58 and 59 to provide relatively shallow channels within which are received the strips of cushioning material 62 and 63; said strips engaging the adjacent edges of the glass face plates. Formed integral with the wing portions 58 and 59 is a rearwardly extending leg 64 embedded in the body portion 15 of the block. The metal spacer strip terminates inwardly of the outer surfaces of the glass face plates and is adapted to be covered by a suitable pointing or calking compound 65. The forward face of the metal strip may be formed with a longitudinally extending groove 66 to assist in anchoring the pointing material in place.

If desired, the metal edge holders may be of the construction illustrated in Fig. 7, wherein the channel portion 42 shown in Fig. 2 is omitted. The metal holder in Fig. 7 is designated in its entirety by the numeral 67 and comprises a flange 68 opposite the edge of the ornamental facing and a load bearing portion 69 opposite the cementitious body portion 15 of the block. The load bearing portion 69 is raised or offset relative to the flange 68 as indicated at 70 so that the said load bearing portion projects beyond the said flange 68. Thus, when the blocks are laid one upon the other, with the load bearing portions 69 of adjacent blocks in contact with one another, the ornamental facings will be spaced slightly from one another and will not support any of the load of the wall. The flange 68 is formed along its outer edge with an inturned lip 71 for retaining the cushioning strip 72, while the load bearing portion 69 has formed integral therewith a flange 73 embedded in the body portion of the block.

In Fig. 8 is illustrated a block 74 provided by the present invention and having associated therewith a metal sash or store front construction designated in its entirety by the numeral 75 for supporting a pane of glass 76. The block 74 comprises generally a cementitious body portion 77 having an ornamental facing 78 secured thereto by a layer of mastic 79 and also by means of the metal edge holders 80.

Although the metal sash or store front construction 75 may be of any conventional or preferred type, it has been shown as comprising a stationary rear section 81 and a movable front section 82 associated with one another for clamping the pane of glass 76 therebetween. More

specifically, the rear section 81 includes a base member 83 having an upstanding longitudinally extending flange 84 at its forward end with which the lower end 85 of the front section 82 is rockably associated. The sections 81 and 82 are secured together by the cooperating clip members 86 and screws 87 carried by the front and rear sections respectively. The particular type of metal sash construction disclosed forms no part of the present invention per se, but is more fully illustrated, described, and claimed in the copending application of C. D. Lowry, filed August 18, 1938, Serial No. 225,591.

The metal sash construction 75 rests upon a metal plate 88 having its forward end 89 turned downwardly and overlapping the upper marginal portion of the ornamental facing of block 74. The metal plate 88 is supported directly upon the load bearing portion 90 of the metal edge holder 86 and is secured thereto by screws 91 which pass downwardly through the base plate 83 of the rear section 81; through the metal plate 88 and also through the load bearing portion 90 into the body portion of the block. In practice, openings for the fastening screws 91 are first punched in the load bearing portion 90 of the metal holder and the screws then threaded downwardly therethrough; said screws being self-tapping screws and forming the threads in the metal holders to thereby firmly secure the metal sash construction to the block. It will be noted that since the load bearing portion 90 of the metal holder extends beyond the edge of the ornamental facing and also beyond the flange overlying the edge of said facing, the metal sash construction 75 can be supported directly upon said load bearing portion without placing any load or strain upon the ornamental facing.

In Fig. 9 is illustrated a building block 92 of the character herein provided having associated therewith a metal coping member designated in its entirety by the numeral 93. The block comprises a cementitious body portion 94 having an ornamental facing 95 secured thereto by a layer of mastic 96. The metal coping member 93 comprises an inverted substantially U-shaped strip comprising a horizontal base portion 97 disposed opposite the edge of the ornamental facing 95 and the depending legs 98 and 99 disposed at the front and rear respectively of said ornamental facing. The base portion 97 is preferably provided with a channel 100 within which is arranged the strip of cushioning material 101 engaging the upper edge of the ornamental facing. The front depending leg 98 is preferably spaced slightly from the ornamental facing so that water will drip from the lower edge thereof and will not run down said facing.

Formed integral with the base portion 97 is a rearwardly and upwardly extending flange 102, while formed integral with the leg 99 is a rearwardly extending web portion 103 terminating in an upwardly inclined flange 104 substantially parallel with flange 102 and forming therebetween a channel 105. Formed at the junction of the web portion 103 and flange 104 is a leg 106 embedded in the cementitious body portion 94 of the block. The numeral 107 represents a sheet of suitable flashing material, preferably of metal, and having its outer end portion folded upon itself as at 108 and inserted within the channel 105. The free end 109 of said flashing is bent over the top of the flange 102 to provide a neat, water-tight construction. If desired, a

layer of mortar 110 may be disposed between the flashing 107 and body portion 84 of the block.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In a building block of the character described, a body portion of cementitious material, an ornamental facing secured thereto comprising plates of glass disposed in spaced edge to edge relation, a metal molding comprising a body member arranged between adjacent glass plates and terminating within the surface contour of the ornamental facing; wing portions extending laterally from said body member and disposed in back of said glass plates and an anchoring portion extending rearwardly from said body portion between said wing portions and embedded in the cementitious body portion of the block, and cushioning means carried by the body member of said metal molding and engaging the adjacent edges of said glass plates.

2. In a building block of the character described, a body portion formed of cementitious material, an ornamental facing secured thereto comprising a plurality of glass plates secured to one surface thereof and disposed in spaced edge to edge relation, a metal molding having a body member arranged between the adjacent edges of the glass plates and terminating within the surface contour of the ornamental facing; wing portions extending laterally from said body member and disposed in back of said glass plates and an anchoring portion extending rearwardly from said body portion between said wing portions and embedded in the cementitious body portion of the block, and cushioning means interposed between the body member of the metal molding and the edges of said glass plates.

3. In a building block of the character de-

scribed, a body portion of cementitious material, an ornamental facing therefor comprising plates of glass disposed in spaced edge to edge relation and secured to said body portion, a metal molding in the form of a spacer strip of integral construction including substantially rectangular body member arranged between adjacent glass plates; wing portions extending laterally from said body member and disposed in back of said glass plates and an anchoring portion extending rearwardly from said wing portions and embedded in the cementitious body portion of the block, said body member terminating within the surface contour of the ornamental facing and being provided along the outer edge thereof with oppositely projecting lips cooperating with said wing portions to provide channels, and cushioning material arranged in said channels and engaging the adjacent edges of the glass plates.

4. In a building block of the character described, a body portion of cementitious material, an ornamental facing therefor comprising plates of glass disposed in spaced edge to edge relation and secured to said body portion, a metal molding in the form of a spacer strip of integral construction including a substantially rectangular body member arranged between adjacent glass plates; wing portions extending laterally from said body member and disposed in back of said glass plates and an anchoring portion extending rearwardly from said wing portions and embedded in the cementitious body portion of the block, said body member being provided along the outer edge thereof with oppositely projecting lips cooperating with said wing portions to provide channels, and cushioning material arranged in said channels and engaging the adjacent edges of the glass plates, the body member of the spacer strip terminating inwardly of the outer surfaces of the glass plates and having its forward face provided with a longitudinally extending groove adapted to receive pointing material therein.

ERLE T. PUTNAM.
